BALL STOP FOR BOWLING ALLEYS

Robert I. Anderson, Grand Haven, Mich., assignor
to The Brunswick-Balke-Collender Company,
Chicago, Ill., a corporation of Delaware

Application September 2, 1944, Serial No. 552,433

14 Claims. (Cl. 273—47)

1

This invention relates to bowling alleys and is particularly concerned with the ball return runway and with means for arresting the ball as it approaches the terminal portion of the runway.

One object of the invention is to provide a new and improved ball stop or retarding device for use in connection with the ball return of a bowling alley.

Another object of the invention is to provide means in combination with the ball return runway for automatically controlling the speed of the ball as it approaches the terminal portion of the runway.

A further object of the invention is to provide means for automatically and temporarily arresting a ball in its return travel on the runway and then automatically releasing the ball to permit its continued movement to the terminal of the runway.

It is also an object of the invention to provide a ball return runway with means adjacent its terminal portion normally positioned to arrest the ball as it approaches said portion, together with delayed-action means set in motion by the arrival of the ball at such arresting means for automatically releasing it therefrom after a brief interval, the runway being inclined from that point toward the terminal, so that the ball will continue its movement when released.

More specifically the invention provides a ball return runway with a normally operative stop device to arrest a ball as it approaches the terminal portion of the runway and with electrically operable means connected for shifting the stop to ball-releasing position, and a switch which is closed by the presence of the ball at the stop and which thus actuates the releasing device to permit the ball to continue along an adjacent inclined section of the runway toward its terminal.

Other objects and advantages of the invention will appear from the following description taken in connection with the drawings, in which—

Fig. 1 is a side elevation of the stop and release mechanism embodied in this invention, the view being taken as a section through the supporting structure as indicated at line 1—1 on Fig. 2, and the position of a bowling ball being indicated in dotted outline.

Fig. 2 is a transverse vertical sectional view taken substantially as indicated at line 2—2 on Fig. 1.

Fig. 3 is a top plan view of the mechanism, with a portion of the structure shown in section as indicated at line 3—3 on Fig. 2.

2

Fig. 4 is a detail section taken as indicated at line 4—4 on Fig. 3.

While the invention is susceptible of various modifications and alternative constructions, it is shown in the drawings and will be described hereinafter in a preferred embodiment; but it is not intended that the invention be limited thereby to the specific embodiment disclosed, but rather, it is intended to cover all modifications and alternative constructions falling within the spirit and scope of the appended claims.

The ball return runway of a bowling alley usually includes a horizontal terminal portion on which the balls are accumulated in a convenient position adjacent the approach end of the alley where they can be picked up as wanted by the bowlers. This terminal portion is somewhat elevated above the level of the main portion of the runway so that an upwardly inclined portion 20 connects them and as the ball traverses this upwardly sloping approach to the terminal its speed is considerably reduced. Fig. 1 shows a fragment of the ball return runway which includes the portion 1 at the highest point of the upwardly inclined section just mentioned, the horizontal portion 2 which is a part of the terminal station at which the balls accumulate, and an intermediate portion 3 which is inclined downwardly from the high point or summit 1 toward the terminal section 2. Upright supports 4 and 5 are disposed, respectively, at opposite sides of the inclined portion 3 of the runway and these supports together with the mechanism carried by them may be enclosed between ornamental side walls 6, 6 indicated in dotted outline in Fig. 1.

The support 4 carries a stop member in the form of a movable wedge 7 which normally projects into the path of the ball, shown in dotted lines at A, as it approaches the terminal portion 2 of the runway. The opposite support 5 is provided with a pad 8 engageable with the ball when it is arrested by the wedge 7. The wedge 7 is carried by an approximately vertical rock shaft 9 and as seen in Fig. 3 this shaft is provided with an arm 10 which is pivotally connected at 11 to one end of a link 12. The link 12 is pivoted at 13 to a link 14 and the opposite end of said link 14 is fulcrumed on a fixed pivot at 15. The links 12 and 14 constitute a toggle, so that when they are disposed with their connecting pivot 13 at one side of the line connecting the pivots 11 and 15, and stopped in this position, they act as a strut to prevent rotation of the shaft 9 in a direction to swing the wedge member 7 away from

the runway and out of engagement with the ball A thereon. A vertically extending plate 16 serves as a stop against which the toggle links 12 and 14 are checked for thus holding the wedge member 7 in operative position, and a spring 17 connected to the link 14 yieldingly maintains engagement of the toggle with the edge of the plate 16.

The plate 16 is in the nature of a bell crank lever, being fulcrumed on a pivot 18. This fulcrum pivot is supported by a bracket 19 secured to the horizontal web 20 which is shown as integral with the uprights 4 and 5 (see Fig. 2) and one limit of movement of the plate 16 about its pivot 18 is determined by engagement of a lug 16a on said plate with said web 20, as seen in Fig. 4. The uprights 4 and 5 also support a motor 21 coupled to a vertical shaft 22 which carries a mechanism similar to a centrifugal governor and which comprises a bracket 23 with a pair of arms 24, 24 depending pivotally therefrom and connected by links 25, 25 to a bracket 26 slidably upon the shaft 22. A cross-pin 27 in the bracket 26 extends through a slot in the shaft to engage a rod 28 telescopically carried in said shaft 22, so that as the shaft rotates the arms 24 are swung outwardly by centrifugal force and thus operate to raise the bracket 26 and the rod 28. The rod is thrust upwardly against the flange 16—b of the bell crank lever or plate 16 and thus rocks the lever against the toggle links 12, 14, swinging their pivot 13 past dead center position or "breaking" the toggle so that it no longer acts as a rigid strut to hold the wedge 7 in ball arresting position.

This release of the wedge 7 is accomplished automatically but with a slight delay after arrival of the ball A at the stop or wedge member 7. As it reaches this position the ball depresses the head 30 of a control rod 31 slidably carried in a bracket 32 on which there is fulcrumed a lever arm 33 carrying a mercury switch 34 which controls the operating circuit for the motor 21. The lower end of the rod 31 engages the arm 33, as seen in Fig. 1, so that depression of the head 30 by the ball A tilts the arm to a position at which the mercury switch 34 closes the motor circuit and thus initiates rotation of the motor and of the shaft 22. As the shaft gains speed the arms 25 are swung outward by centrifugal force as already described and thus actuate the rod 28 and lever 16 to "break" the toggle 12, 14. Since the ball A is resting on the downwardly inclined portion 3 of the ball return runway the weight of the ball operates to swing the wedge member 7 aside so that the ball may pass and roll onto the horizontal terminal portion 2 of the runway.

As the ball rolls off the head 30 of the control rod 31 the weight of the arm 33 returns it to its initial position so that a brake shoe 35 carried by arm 33 is brought into engagement with a brake wheel in the form of a disc 36 secured to the shaft 22 for rotation therewith. The return of the arm 33 to normal position thus opens the circuit of the motor 21 and simultaneously applies the brake 35 to the disc 36, arresting the shaft 22 and permitting the rod 28 to recede downwardly away from the bell crank lever 16. At the same time the spring 17 operates to return the toggle 12, 14 to its initial position past dead center, thus swinging the wedge member 7 into ball arresting position and locking it, ready to receive the next ball which arrives over the crest or summit 1 of the ball return runway. Fig. 1 includes a simple wiring diagram showing feed wires 40 and 41

for the motor 21 with leads 42 and 43 extending from the feed wire 41 into the mercury switch 34.

I claim as my invention:

1. In a bowling alley, in combination with a ball return runway having a portion inclined downwardly toward its terminal, a ball stop comprising stationary supports disposed, respectively, at opposite sides of said inclined runway, with a ball engaging means on each of said supports, one of said means including a stop member mounted for movement horizontally into and out of the path of a ball and normally extending into said path, electrically actuated mechanism operable to release said member for movement away from said path, a single switch device operable to closed position by the ball substantially upon its arrival at said stop member, and an electric circuit controlled by said switch serving to energize said mechanism, said mechanism for releasing the stop member operating while the ball is motionless in the runway at the stop member at the position where the switch was closed.

2. In a bowling alley, in combination with a ball return runway having a portion inclined downwardly toward its terminal, a ball stop including a stop member mounted for movement into and out of the path of a ball on said inclined portion and normally extending into said path, electrically actuated mechanism operable to release said member for movement away from said path, a normally open switch with means operable by the ball to close said switch substantially upon arrival of the ball at said stop member, an electric circuit controlled by said switch serving to energize said mechanism for releasing the stop, means automatically opening the switch after the ball has passed the released stop, and means automatically returning the stop to its normal operative position said mechanism for releasing the stop member operating while the ball is motionless in the runway at the stop member at the position where the switch was closed.

3. In a bowling alley, in combination with a ball return runway having a portion inclined downwardly toward its terminal, a ball stop including a rock shaft extending adjacent said inclined portion with a wedge member carried by said shaft and normally extending into the path of a ball on the inclined portion, means normally holding said shaft against rotating in a direction to swing the wedge member away from said path, and means rendered operative by the arrival of a ball in engagement with said wedge member, said means releasing the first mentioned means and thereby the shaft and thus permitting the ball to force the wedge aside and roll down the runway toward the terminal.

4. In a bowling alley, in combination with a ball return runway having a portion inclined downwardly toward its terminal, a ball stop including a rock shaft extending adjacent said inclined portion with a wedge member carried by said shaft and normally extending into the path of a ball on the inclined portion, an arm on said shaft, a pair of links pivoted together forming a toggle and connecting said arm with a fixed fulcrum, stop means engaged by said toggle when its connecting pivot is at one side of its dead center position, whereby the toggle acts as a strut to prevent rotation of the shaft, and means rendered operative by the arrival of a ball in engagement with the wedge member, said means shifting said stop means to carry the toggle pivot to the other side of dead center, permitting the toggle to buckle so that the wedge

can swing aside in response to the pressure of the ball against it.

5. In a bowling alley, in combination with a ball return runway having a portion inclined downwardly toward its terminal, a ball stop including a stop member normally projecting into the path of a ball on said inclined portion, releasable means normally effective to hold said stop member in said position, an electric motor with a control switch therefor including an operating member actuated by a ball upon its arrival at the stop member, and a centrifugal device operable by rotation of the motor, with connections from said device to said means for releasing said means and thereby the stop to permit the ball to proceed down the incline of the runway.

6. In a bowling alley, in combination with a ball return runway having a portion inclined downwardly toward its terminal, a ball stop including a stop member normally projecting into the path of a ball on said inclined portion, an electric motor with a control switch therefor including an operating member actuated by a ball upon its arrival at the stop member, and a centrifugal device including a shaft rotated by the motor, a pair of arms pendulously pivoted to the shaft, a bracket slidable along the shaft and linked to said arms, and a member telescoped with the shaft and movable axially by said bracket, together with means transmitting the movement of said telescopic member to shift the stop member from ball arresting position.

7. In a bowling alley, in combination with a ball return runway having a portion inclined downwardly toward its terminal, a ball stop including a stop member normally projecting into the path of a ball on said inclined portion, a toggle device which normally locks the stop member in its projecting position, an electric motor with a control switch therefor including an operating member actuated by a ball upon its arrival at the stop member, and a centrifugal device operable by rotation of the motor to buckle the toggle past dead center for releasing the stop to permit the ball to proceed down the incline of the runway.

8. In a bowling alley, in combination with a ball return runway having a portion inclined downwardly toward its terminal, a ball stop including a stop member normally projecting into the path of a ball on said inclined portion, a toggle device which normally locks the stop member in its projecting position, an electric motor with a control switch therefor including an operating member actuated by a ball upon its arrival at the stop member, and a centrifugal device operable by rotation of the motor to buckle the toggle past dead center for releasing the stop to permit the ball to proceed down the incline of the runway, together with spring means automatically returning the stop member to projecting position and returning the toggle to locking position.

9. In a bowling alley, in combination with a ball return runway having a portion inclined downwardly toward its terminal, a ball stop including a stop member normally projecting into the path of a ball on said inclined portion, an electric motor with control means therefor including a head normally projecting into the runway in position to be depressed by a ball upon its arrival at the stop member, a tiltable switch connected in the motor circuit, and means transmitting motion from said head to said

switch for tilting it into circuit-closing position when the head is depressed, and a centrifugal device operable by rotation of the motor with connections from said device for releasing the stop to permit the ball to proceed down the incline of the runway.

10. In a bowling alley, in combination with a ball return runway having a portion inclined downwardly toward its terminal, a ball stop including a stop member normally projecting into the path of a ball on said inclined portion, an electric motor with control means therefor including a head normally projecting into the runway in position to be depressed by a ball upon its arrival at the stop member, a tiltable switch connected in the motor circuit, and means transmitting motion from said head to said switch for tilting it into circuit-closing position when the head is depressed, said transmitting means including a rockable lever arm, a centrifugal device operable by rotation of the motor with connections from said device for releasing the stop to permit the ball to proceed down the runway, a brake wheel driven by the motor, and a brake shoe on said rockable lever disengageable from the wheel by the depression of said head and engageable with said wheel when the head is released as the ball moves down the incline.

11. In a bowling alley having a ball return runway including a portion inclined downwardly toward its terminal, a ball stop comprising a rock shaft extending adjacent said inclined portion with a stop member operatively associated with said shaft and normally extending into the path of a ball on the inclined portion, means normally holding said shaft against rotation in a direction to swing the stop member away from said path, and means rendered operative by the arrival of a ball in engagement with said stop member, said means releasing said holding means and thereby the shaft and thus permitting the ball to force the stop member aside and roll down the runway toward said terminal.

12. In a bowling alley having a ball return runway including a portion inclined downwardly toward its terminal, a ball stop comprising a movable stop member normally projecting in ball engaging position into the path of a ball on said inclined portion, means adjacent said stop member and operatively connected thereto normally maintaining said member in ball engaging position, means operated by the ball upon contact of the ball with the stop member for withdrawing said member from its ball engaging position, and means operatively connected to said stop member for automatically returning said stop member to ball engaging position after the ball has passed therebeyond.

13. In a bowling alley, in combination with a ball return runway having a portion inclined downwardly toward its terminal, a ball stop including a stop member normally projecting into the path of a ball on said inclined portion, a base member adjacent thereto, a toggle device including a pair of links having one end of each pivotally connected together with the other end of the first link operatively and rotatably attached to the stop member and the other end of the other link rotatably attached to said base member, said links normally being substantially aligned to lock the stop member in its projecting position, an electric motor with a control switch therefor including an operating member actuated by a ball upon its arrival at the stop member, and means operable by rotation of the motor

7
to buckle the toggle past dead center for releasing the stop to permit the ball to proceed down the incline of the runway, said means including a movable member bearing laterally against said links for buckling the same.

14. In a bowling alley, in combination with a ball return runway having a portion inclined downwardly toward its terminal, a ball stop comprising stationary supports disposed, respectively, at opposite sides of said inclined runway, 10 with a ball engaging means on each of said supports, one of said means including a stop member mounted for movement horizontally into and out of the path of a ball and normally extending into said path, toggle means normally locking said stop member in a position in the path of a ball, electrically actuated mechanism having a member bearing against said toggle means and operable to buckle said toggle means to release said stop member for movement away from 15 20

said path, a switch device operable by the ball substantially upon its arrival at said stop member, and an electric circuit controlled by said switch serving to energize said mechanism, said mechanism when energized moving its said member laterally against said toggle means to move the same and the stop member into unlocked position.

ROBERT I. ANDERSON.
